NORBORNE BERKELEY, OF ALDIE, VIRGINIA.

Letters Patent No. 93,953, dated August 24, 1869.

IMPROVED DEVICE FOR SUPPORTING WAGON-BEDS.

The Schedule referred to in these Letters Patent and making part of the same.

To all whom it may concern:

Be it known that I, NORBORNE BERKELEY, of Aldie, in the county of Loudoun, and State of Virginia, have invented a new and useful Device for Supporting and Securing Wagon-Beds; and I do hereby declare the following to be a full, clear, and exact description of the same, reference being had to the accompanying drawing, which is made a part of this specification.

The object of my invention is to adapt a wagon-bed or body to be supported on its bolster, either solidly, or through the medium of springs, as required, and to adapt the requisite change or adjustment to be readily and expeditiously made.

It consists in the employment or use of suitable springs, applied around the standards of the frame, and suitable brackets, applied to the bed, and adapted to be held at different points in the vertical height thereof, so as to rest on said springs, or be supported thereof, said provisions also serving to secure the bed on the frame.

Figure 1, in the drawing, is a side elevation of a wagon having my invention applied, the bed being shown supported on the springs.

Figure 2 is a transverse section on the line $x x$, fig. 1, representing, in black, the bed resting solidly on the bolsters, and, in red, its position as represented in fig. 1.

a a represent the usual bolsters, and *b b*, the usual standards mounted thereon, for the securement of the bed.

c represents the "bed" of the wagon.

d d represent the springs applied to the standards *b*;

e e, the brackets attached to the bed *c*; and

f f f f, fig. 2, the pairs of sockets provided in the sides of the bed *c*, for the reception of the brackets *e* in their two positions

g g represent the stems of the brackets *e*, adapted for engagement with the sockets *f f*.

h h represent metallic plates, applied internally and externally of the sides of the bed *c*, to strengthen the sockets *f f*, in the form shown.

With the bed supported on the springs, as shown in fig. 1, and in red in fig. 2, an easy-riding conveyance is secured; and with it supported directly on the bolsters, as represented in black in fig. 2, the wagon is adapted, with equal facility, for carrying heavy loads, in connection with which springs of sufficient sensitiveness to adapt the wagon for easy riding would be useless, and would only be destroyed.

To convert the wagon, the bed is removed, the brackets withdrawn, and inserted in the other sockets, and the bed then replaced.

With said brackets held in the lower sockets, the bed is supported on the springs; with them in the up-

per sockets, it rests solidly on the bolsters, the brackets being held above the springs, as indicated in fig. 2.

The bolsters *a* and the running-gear of the wagon may be of any desired form.

The standards *b* are, preferably, made cylindrical, to adapt them for the reception of cylindrical springs, and are arranged at such greater distance apart than the width of the bed as to accommodate the springs in their most distended condition.

The bed *c*, with the exception of the provision for the reception of the brackets, may be of any desired construction, and, with said brackets of the construction shown, may have the usual cleats, for its longitudinal securement, omitted.

The springs *d* may be cylindrical in form, and of coiled wire, as shown, or of any other suitable form and material.

The brackets *e*, preferably, consist of rings, adapted to engage over the standards *b*, as shown, as providing, with the least weight, a good bearing for the springs, and serving, in addition, to support or secure the bed longitudinally and laterally; but their form may obviously be varied. Their stems *g*, also, preferably, consist of straight screws, having shoulders, to limit their insertion, as affording a ready and expeditious mode of attachment, and, with said brackets, engaging with the standards, as proposed, effectually preventing accidental displacement; but may be of other form, if preferred, and the sockets *f f*, for their reception, correspondingly varied.

The plates *h h* are, preferably, employed, for the support of the sockets *f f*, in the form shown, but are not essential.

The standards *b*, to which the springs are applied, preferably, constitute or take the place of the usual standards, but may obviously be employed in connection therewith, if preferred.

Having thus described my invention,

I claim, and desire to secure by Letters Patent—

1. In combination with the sills *a*, standards *b*, and bed *c*, of a wagon, and springs *d*, applied around said standards *b*, the brackets *e*, attached to the bed *c*, and adapted to be held in sockets *f f*, at different points in the height of the bed, so as to rest on or be supported off of said springs, substantially as represented and described, for the purpose set forth.

2. In the described combination, the adjustable brackets *e e*, adapted to longitudinally and laterally support or secure the bed, substantially as described.

To the above specification of my device for supporting and securing wagon-beds, I have signed my hand, this 15th day of June, A. D. 1869.

Witnesses: NORBORNE BERKELEY.

JOHN GRINNELL,
W. B. DEMING.
